UNITED STATES PATENT OFFICE

153,894

DESIGN FOR A DUTCH OVEN

Albert D. Mortrude, Detroit, Mich., assignor to
Kromex Corporation, Cleveland, Ohio, a cor-
poration of Ohio

Application June 12, 1947, Serial No. 139,616

Term of patent 14 years

(Cl. D44—1)

To all whom it may concern:

Be it known that I, Albert D. Mortrude, a citizen of the United States, residing at Detroit, county of Wayne, and State of Michigan, have invented a new, original, and ornamental Design for Dutch Oven, of which the following is a specification, reference being had to the accompanying drawing, forming a part thereof.

Fig. 1 is a plan view of a dutch oven, showing my new design;

Fig. 2 is a side elevational view of the dutch oven;

Fig. 3 is an end elevational view of the dutch oven;

Fig. 4 is a fragmentary cross-sectional view of the cover, taken on the line 4—4 of Fig. 2, and

Fig. 5 is a fragmentary cross-sectional view of the oven body taken on line 5—5 of Fig. 2.

I claim:

The ornamental design for a dutch oven, substantially as shown.

ALBERT D. MORTRUEDE.
